UNITED STATES PATENT OFFICE

102,369

DESIGN FOR A SPOON OR SIMILAR ARTICLE

Frederick Hoyle, Lambertville, N. J., assignor to The Stieff Company, Baltimore, Md., a corporation of Maryland

Application October 30, 1936, Serial No. 65,598

Term of patent 14 years

To all whom it may concern:

Be it known that I, Frederick Hoyle, a citizen of the United States, residing at Lambertville, in the State of New Jersey, have invented a new, original, and ornamental Design for a Spoon or Similar Article, of which the following is a specification, reference being had to the accompanying drawing, forming a part thereof, in which

Figure 1 is a side view of a spoon showing my new design; and

The back of the spoon shown in Figures 1 and 2 is plain.

I claim:

The ornamental design for a spoon or similar article, substantially as shown and described.

FREDERICK HOYLE.
